United States Patent Office

Des. 184,803
Patented Apr. 7, 1959

184,803

INDICATING CONTROL PANEL OR SIMILAR ARTICLE

David C. Eisendrath, Chicago, Ill., assignor to Cory
Corporation, Chicago, Ill., a corporation of Delaware

Application July 10, 1957, Serial No. 46,897

Term of patent 7 years

(Cl. D26—1)

Figure 1 is a front elevational view of an indicating control panel or similar article embodying my new design;

Figure 2 is a side elevational view thereof; and

Figure 3 is a top plan view thereof.

The dominant portion of the design is shown in solid lines.

I claim:

The ornamental design for an indicating control panel or similar article, as shown and described.
